RADIATOR TESTING AND REPAIR
APPARATUS

Clyde T. Walker, Orlando, Fla.

Application August 5, 1937, Serial No. 157,602

4 Claims. (Cl. 73—51)

This invention relates to an apparatus for testing and repairing leaks in radiators.

The object of this invention is to provide means for supporting a radiator so that it can be filled with air and submerged to disclose leaks.

Another object of the invention is to provide means to hold the radiator in an upright position elevated above the water so that any solder which may be dropped will fall into the water from where it can be reclaimed and reused.

A further object of the invention is to provide a piston operated by compressed air and operably connected by levers to the supporting means for the radiator whereby the radiator can be raised or submerged.

Other objects and advantages of the invention will hereinafter become more fully apparent from the following specification of which the drawings form a part, and wherein:

20 Figure 1 is a perspective view of the invention, Figure 2 is a cross sectional view on the line 2—2 of Figure 1,

25 Figure 3 is a cross sectional view on the line 3—3 of Figure 1,

Figure 4 is an enlarged vertical sectional view of the cylinder containing the reciprocating piston shown in elevation, and

30 Figure 5 is an enlarged vertical sectional view of the valve controlling the air supply.

Referring more particularly to the drawings wherein like reference characters designate like or corresponding parts in the different views, 10 designates generally a table provided with a receptacle or container 11 for water.

35 A frame 12 comprising a rectangular member 13 supported by the members 14 and 15 which are connected to the crossbar 16 having downturned ends 17 secured in pipes 18 is mounted above the container 11. A rack or tray 19 is mounted crosswise on member 13. Pipes 18 are slidably mounted in sleeves 20 secured to the frame of table 10 surrounding container 11 by straps 21. The lower ends of pipes 18 are provided with forked sockets 22 in which are mounted 45 ed rollers 23.

Secured to the bottom of table 10 are the transverse beams 24 to which are connected the V-shaped braces 25 which are secured to a plank 26 which rests upon the supporting surface.

50 A plate 27 provided with depending sides 28 which are secured to the braces 25 supports a cylinder 29 provided with a removable top and bottom 30 and 31 respectively which are held assembled by the bolts and nuts 32 which extend 55 through plate 27, bottom 31 and top 30.

A piston 33 slidably mounted in cylinder 29 is provided with a piston rod 34 extending through plate 27 and bottom 31 and having an enlarged disk like end 35. Levers 36 are pivotally supported by axles 37 journaled in sides 28. The adjacent ends of levers 36 are provided with rollers 38 to engage the disk 35, and the rollers 23 of pipes 18 engage adjacent the opposite end of levers 36 as best seen in Figure 3. Piston 33 is normally urged upward by coil springs 39 connected to levers 36.

A pipe 40 connected to the top 30 extends lengthwise of container 11, then across and up the side of table 10 to connect with a valve casing 41. As best seen in Figure 5 casing 41 has one opening at its top, and two at the bottom which communicate with pipes 42 and 43 secured to sleeve 44 in which the tubular depending portion of casing 41 is mounted. A valve 45 provided with a tapered opening 46 and controlled by a handle 47 selectively controls pipes 40, 42 and 43. Pipe 42 is an exhaust pipe, and pipe 43 leads to a tank of compressed air, (not shown). In pipe 43 is a needle valve 48.

As best seen in Figures 1 and 2, a pipe 49 is 25 connected to pipe 40 and extends upwardly along one end of the frame surrounding container 11. Pipe 49 is provided with an outlet 50 to which is connected a flexible hose 51. Pipe 49 is also provided with an outlet 52 controlled by a valve 53. 30 Valve 54 mounted in pipe 49 beneath outlets 50 and 52 controls the supply of air passing through pipe 49.

A brace 55 is pivotally connected at 56 to member 16 to support a radiator, shown in dotted lines at 57, in an upright position, for repairing when the radiator 57 is not long enough to lean against member 16, or if it is desired to lay radiator 57 on its side. For such use brace 55 is swung to the dotted line position of Figure 2, 40 in which position it rests against members 15, which extend almost vertically for this purpose. For testing, radiator 57 lays flat on rack 19.

Table 10 is provided at one end with a work shelf 58 which may be used to hold tools or the like.

Cylinder 29 is partially filled with oil as indicated at 59 in Figure 4.

From the foregoing it will be obvious that when air under pressure is admitted to cylinder 29 by 50 opening valve 48 and moving handle 47 to the position shown in Figure 5, air will pass through pipes 43 and 40 to cylinder 29 to depress piston 33 to operate levers 36 to raise pipes 18 and frame 12. With frame 12 in a raised position 55

radiator 57 is laid flat on rack 19. All but one of the openings in radiator 57 is then plugged, and hose 51 is attached to this opening. With valve 53 closed valve 54 is then opened admitting 5 air from pipe 40 through pipe 49 and hose 51 to radiator 57. When sufficient pressure is obtained valve 54 is closed. Handle 47 is next moved upwardly so opening 46 will communicate with exhaust pipe 42 to allow the air in cylinder 29 10 to be exhausted. As this occurs, the weight of radiator 57 will cause frame 12 to move downwardly from the position shown in Figure 1 to its position in Figure 3, with pipes 18 depressing the outer ends of levers 36 to raise piston 33. In 15 its lowered position radiator 57 is submerged so that bubbles will disclose the leaks in the radiator. By applying pressure as heretofore explained to cylinder 29 frame 12 can again be raised and radiator 47 set upright for repair. In this position any solder that may drop will fall into the 20 water in container 11 from where it can be recovered and reused.

It is to be understood that only the preferred embodiment of the invention has been shown 25 and described, the right being reserved to make such changes as will not depart from the spirit and scope of the invention as claimed.

I claim as my invention:

1. In a radiator testing and repair apparatus, a 30 water container, a supporting member disposed above said container and having depending ends, a reciprocating piston disposed beneath said container, operating means for said piston, levers pivotally mounted adjacent said piston and having 35 their adjacent ends engageable therewith and operable thereby, the opposite ends of said levers being connected to the depending ends of said supporting member to raise and lower it when the piston is operated, a frame having upwardly 40 extending arms secured to the supporting member and vertically movable relatively to said container thereby to submerge or raise a radiator supported by the frame, and means to supply air under pressure to said radiator to detect leaks 45 therein when submerged.

2. In a radiator testing and repair apparatus, a water container, a supporting member dis-

posed above said container and having depending ends, a reciprocating piston disposed beneath said container, operating means for said piston, levers pivotally mounted adjacent said piston and having their adjacent ends engageable therewith and operable thereby, the opposite ends of said levers being connected to the depending ends of said supporting member to raise and lower it when the piston is operated, a frame having upwardly extending arms secured to the supporting member and vertically movable relatively to said container thereby to submerge or raise a radiator supported by the frame, means to supply air under pressure to said radiator to detect leaks therein when submerged, and a tray slidably 15 mounted on said frame and adapted to support radiators of various sizes in the container, said supporting member cooperating with the tray to support a radiator in an upright position for repair. 20

3. A device as in claim 2, and means pivotally connected to said supporting member and engaging certain of said upwardly extending arms and adapted to support small size radiators in an upright position. 25

4. In a device of the class described, a receptacle adapted to contain water, a rod disposed longitudinally of and above said receptacle having depending arms adapted to be slidably mounted in sleeve members secured adjacent the opposite ends of the receptacle, a piston mounted centrally of and beneath the receptacle, operating means to project said piston downwardly, levers pivotally mounted adjacent said piston and having their adjacent ends in engagement therewith, spring means urging said ends upwardly to raise the piston, said levers extending longitudinally of the receptacle with their free ends in engagement with said depending arms, a frame secured to said rod and depending into 30 the receptacle, said piston being operable to raise and lower the frame to submerge or raise a radiator supported thereby, and means to supply air under pressure to the radiator to detect leaks 35 therein when submerged in the receptacle. 40 45

CLYDE T. WALKER.
